WILLIAM E. BROCK AND STEPHEN H. HUBBARD, OF CHATTANOOGA, TENNESSEE.

PACKING-TABLE.

1,028,670.

Specification of Letters Patent.

Patented June 4, 1912.

Application filed March 9, 1911. Serial No. 613,294.

To all whom it may concern:

Be it known that we, WILLIAM E. BROCK and STEPHEN H. HUBBARD, citizens of the United States, residing at Chattanooga, in 5 the county of Hamilton and State of Tennessee, have invented new and useful Improvements in Packing-Tables, of which the following is a specification.

This invention relates to a revolving 10 packing table for facilitating the disposition of candy devices or other material in boxes or packages, or in some uses to so arrange the parts of packages, boxes or other articles that the latter may be readily assembled.

The primary object of the invention is to provide a revolving packing table having means for holding candies of various kinds in separate compartments which are successively brought adjacent to a packer to enable the latter to conveniently pick up different shaped and flavored pieces that enter into the make-up of an original package whereby uniform packages are produced 25 having the same assortment therein with every piece in the same place in every package so that all the packages will be exact duplicates.

A further object of the invention is to 30 provide means for rendering the packing of boxes or other inclosures expeditious and to avoid marring of certain delicate candies, such as chocolates and bonbons, while being packed.

A still further object of the invention is to provide a revolving packing table that takes up considerable less floor space than the oblong stationary table usually employed and without detracting from the 40 capacity of the said usual packing tables.

With these and other objects and advantages in view the invention consists in the construction and arrangement of the several parts which will be more fully hereinafter 45 described and claimed in preferred form, the drawings illustrating one practical embodiment of the table and which may be modified in proportions, dimensions and details of construction as well as operating 50 means without departing from the scope of the claims.

In the drawings: Figure 1 is a side elevation of a revolving packing table embodying the features of the invention. Fig. 2 55 is a similar view of the table broken away in part and shown in section. Fig. 3 is a

detail view of a part of the operating mechanism. Fig. 4 is a top plan view of the table showing a portion thereof broken away. Fig. 5 illustrates detail views of one 60 of the supply receptacles or boxes in which candies or articles of the same kind are originally stored.

The table comprises three essential parts, consisting of an outer fixed rim or section 2 65 which constitutes the packing rest for the operatives, a rotatable annular carrier 3 for holding the receptacle containing the candies or materials of the same kind in each and elevated above the fixed rim or ledge 2, 70 and an inner fixed support 8 of circular form which will be utilized as a means for holding the empty boxes or packages to be filled within easy reaching distance of the operatives.

The fixed rim or support 2 has a depending flange or guard 1, and attached thereto is a plurality of radial arms or supports 6 which project inwardly and are secured to the head of a pedestal or stand 18, 80 which is hollow and has a post 19 extending upwardly through the center and above the same and attached to the under side of the center of the inner circular support 8. The annular carrier 3 is also provided with a depending guard wall or flange 4 which terminates below the upper surface of the fixed rim or support 2, and extending radially inward from the said carrier is a plurality of arms or spokes 7 which are fixed to a 85 gear 10 having free rotative movement around the post 19, the upper end of the latter being preferably secured to the support 8 through the medium of a plate 9. Between the lower central portion of the 90 gear 10 and the head of the pedestal or stand 18, antifrictional balls 11 are interposed to ease the movement of the carrier 3. The movement of the carrier 3 is also eased by the provision of antifrictional rollers 26 100 supported on the arms 6 and engaging the under side of the said carrier, as clearly shown by Figs. 2 and 4.

The rotating carrier 3 is provided with a plurality of partitions radially disposed 105 thereon and dividing the top surface into equal spaces for the purpose of holding trays or containing devices in which the candy or other articles to be packed are originally disposed. These partitions 3^b 110 provide compartments open at their inner and outer ends, of a shape corresponding to

that of the trays or containing devices for the candies or articles of one kind so that the same kind of candies or articles may be disposed between each two partitions, the 5 partitions by their inward convergence preventing the trays, as 3^x, from being pushed inwardly beyond a predetermined distance.

The trays containing the distinct kinds of candies or articles to be packed are of the 10 form shown by Fig. 5 and are pushed inwardly between the partitions 3^b from the outer edge of the carrier 3, and the side walls of the said trays snugly engage the partitions so that the trays will be prevented 15 from slipping out of place and held positively in fixed position during the rotation of the carrier. As the trays 3^x become emptied they will be withdrawn and replaced by trays containing similar candies 20 or articles. The shape of the trays 3^x also facilitates the close packing of the same on shelves by alternately reversing each tray and bringing the sides into contact.

On the lower portion of the pedestal or 25 stand 18 a bracket 24 is fixed, and thereon is mounted a motor 17, preferably of the electric type, having a worm shaft 20 projecting therefrom, as shown by Fig. 3, the said worm shaft being held in continual 30 mesh with a worm wheel 14 keyed on a vertical shaft 13 supported at its lower end in a bracket 16 and at its upper portion rotatably held in a bracket 15 secured to the head of the pedestal or stand 18. On 35 the upper end of the shaft 13 a pinion 12 is fixed and held in continual mesh with the gear wheel 10, and by this means the carrier 3 is regularly rotated. It will be understood that the electric motor 17 will 40 be supplied with a current of electricity from a suitable source of generation at a distance from the table. The means for operating the carrier 3 as just explained is very compact, but the invention is not in 45 the least limited by this particular operating means and it is proposed to utilize any suitable driving mechanism.

In fastening the several parts, such as the arms 6 and 7 and the plate 9 respectively 50 to the fixed rim 2, carrier 3, support 8 and head of the pedestal or stand 18, suitable fastening devices 21, 22 and 23 will be used.

In the use of the table a number of operatives are seated around the same with a 55 box or package to be filled in front of each. The driving mechanism is set in motion and the carrier regularly rotated to bring the trays 3^x successively in front of each operative who picks out a piece of candy 60 or other article contained in each tray and deposits it in the containing boxes in regular order so that each box may contain the same kinds of candy or articles in the same order and all the boxes will therefore be 65 uniformly packed. As each box is filled the

operative will put the same to one side in any suitable receptacle therefor and immediately take an empty box or package from the support 8 without requiring departure from the table. It will be seen that boxes or 70 packages may thus be quickly and reliably packed without marring or scoring the pieces forming the contents, the latter being a materially advantageous feature in view of the delicacy of some candies, such as 75 chocolates and bonbons.

The table has been primarily devised for packing candy, but as hereinbefore indicated it may be used for assembling other articles in packages, but in some instances 80 it may conveniently serve as a means for carrying separate parts of various devices which will be individually picked up and associated or packed as may be desired.

One of the most important advantages of 85 the improved rotary packing table is the economy in space without affecting capacity as compared to the ordinary oblong packing tables, and, further, placing before each operative in succession the trays containing 90 the different kinds of candies or articles to be packed without requiring the operative to reach for containing devices having the candies or articles therein to be packed.

What is claimed as new is:

95

1. In a packing table, an outer fixed rim, a central fixed support having a horizontally flat unobstructed top surface elevated above the rim and always remaining at the same elevation, a rotatable annular carrier 100 between the said rim and support and having its upper surface on a fixed level with the upper surface of said support and surrounding the latter, and a pedestal for the table as a whole and located centrally with 105 respect to the latter, the space under the fixed rim being clear.

2. In a packing table, an outer fixed rim, a central fixed support having a horizontally flat unobstructed top surface always 110 remaining at the same elevation and disposed above the plane of the rim, a rotatable annular carrier between the said fixed rim and support and having its upper surface on a level with the upper surface of 115 said support and provided with a plurality of vertical partitions extending transversely thereover in radial planes to form spaces which are fully open at their outer and inner extremities and upper portions 120 to receive receptacles containing candy or material to be packed, and a pedestal for supporting the table as a whole.

3. In a packing table, an outer fixed rim, a central fixed support having a horizontally flat unobstructed top surface elevated above the rim and always remaining at the same elevation, a rotatable annular carrier 125 between the said rim and support and having its upper surface on a level with the 130

upper surface of said support and surrounding the latter, a pedestal for the table as a whole and located centrally with respect to the latter, the space under the fixed rim 5 being clear, and means for maintaining a regular rotation of the carrier.

4. In a packing table, an annular rotatable carrier having a plurality of radially arranged inwardly converged partitions 10 disposed on the upper surface thereof and extending fully across the same, the spaces between the partitions being open at their inner and outer extremities and at their top portions to receive receptacles containing candy or material to be packed, the said 15 receptacles being prevented from being

pushed inwardly beyond the inner terminals of the partitions, combined with a fixed rim arranged outside of the carrier and below the plane of the latter to hold packing 20 receptacles to receive the candy or material from the receptacles held between the partitions.

In testimony whereof we have hereunto set our hands in presence of two subscribing 25 witnesses.

WILLIAM E. BROCK.
STEPHEN H. HUBBARD.
